UNITED STATES PATENT OFFICE.

JOHN WILLOUGHBY, OF NEW YORK, N. Y., ASSIGNOR OF ONE-HALF TO GEORGE W. BAYLEY, OF BROOKLYN, NEW YORK.

INTERNAL-COMBUSTION ENGINE.

1,077,381.

Specification of Letters Patent.

Patented Nov. 4, 1913.

Original application filed June 9, 1911, Serial No. 632,153. Divided and this application filed January 4, 1912. Serial No. 669,306.

To all whom it may concern:

Be it known that I, JOHN WILLOUGHBY, a citizen of the United States, and a resident of the borough of Brooklyn, county of 5 Kings, city and State of New York, have invented a certain new and useful Improvement in Internal-Combustion Engines, of which the following is a specification.

The object I have in view is the production of an internal combustion engine, of the two-cycle type, having a compressing cylinder and a working cylinder, and a combined compressing and working piston, with superior devices for preventing leakage between the compression and working chambers, and vice versa. These and further objects will more fully appear in the following specification and accompanying drawings, considered together or separately.

20 This application for patent is a division of an application for patent filed by me June 9th, 1911, Serial No. 632,153.

In the drawings, Figure 1 is a plan view of an apparatus embodying my invention, 25 the plan being partly in section, taken on the line 1-1 of Fig. 2. Fig. 2 is a side elevation of the same, also partly in section, the section being taken on the line 2-2 of Fig. 1. Fig. 3 is a section, on the line 3-3 30 of Fig. 2; and Fig. 4 is a detailed perspective view in section of the bull ring and lower plate.

In all of the views, like parts are designated by the same reference characters.

35 The particular embodiment of the invention shows in illustration a two cylinder engine. It will be understood that the principles disclosed in this apparatus may be applied in an engine consisting of a different 40 number of cylinders.

Referring to the drawings, the cylinders 1 and 2 are shown as being vertical, although their position is immaterial, and each contains a piston which is connected to the usual crank shaft. The cylinders have the usual heads and water jackets, as shown. The cylinders are alike, and each comprises combustion chambers 3 and 3^a, and compression chambers 4 and 4^a, the compression 45 chambers 4 and 4^a being of larger diameter than the combustion chambers 3 and 3^a. In the combustion chambers are located working pistons 5 and 5^a, and in the compression chambers are located compression pistons 6

and 6^a, the working pistons and the compression pistons being preferably combined in one structure, as shown. The usual connecting rods 7 and 7^a, shaft 8, and cranks 9 and 9^a are provided, the cranks being 180° apart. It is apparent that while the pistons in one cylinder go up, those in the other go down, and that when those in one reach the extreme of their upper stroke, those in the other reach the extreme of their bottom stroke.

On the sides of the cylinders is the valve casing 25. In this valve casing are piston valves 26 and 26^a connected together by a rod as shown, one end of which is actuated by a cam appropriately rotated by suitable mechanism so as to turn in time with the main shaft, as is described in my copending application before referred to. Between the two valves 26 and 26^a is a passage 27 from the carburetor (not shown). This passage 75 communicates with the valve chest 10, which in turn communicates at each end through the ports 11, 11^a, to the compression chambers 4, 4^a. Suitable ports 12, 12^a serve as a means of communication from the compression chambers 4 to the valve chest 10. Cross passages 13, 13^a communicate with the valve chest by means of ports 14, 14^a. Ports 15, 15^a connect the cross passages to the combustion chambers. At the upper corner of 85 each of the working pistons 5 is a port 16, which is adapted to register with the ports 15, 15^a when the piston is at the bottom of its stroke. The usual deflector is provided adjacent to the port 16.

17 is the exhaust port.

The operation of the structure described is as follows: During the down stroke of the right-hand piston, as shown, carbureted air will be drawn through the port 9 into 95 the valve chest 10, thence through the port 12^a into the compression chamber 4^a, the valve 26^a being in such position that the port 12^a is uncovered. During the up-stroke of the left-hand piston the port 12 is covered and the ports 11 and 14 are uncovered. The explosive mixture previously drawn into the compression chamber 4 will be compressed in that chamber, and will be passed through the ports 11 and 14, and through 100 the cross passages 13 into the port 15^a, and will be compressed in these passages. As soon as the working piston 5^a in the right-

hand cylinder is at the bottom of its stroke, the port 16 in the piston will register with the valve casing port 15^a, and the charge which had been previously compressed in the compression cylinder on the opposite side will pass through the port 15^a into the combustion chamber 3^a, scavenging the latter, and driving out, through the exhaust port, the products of combustion from the previous explosion. It will be seen that as the compressing piston 6^a in the right-hand cylinder is ascending, the working piston 5 of the left-hand cylinder will be descending. Consequently, when the working piston 5 has reached the bottom of its stroke, and has registered its port 16 with its port 15, the compressing piston 6^a of the right-hand cylinder will be at the uppermost part of its stroke, having compressed the explosive mixture and this mixture under pressure will immediately pass into the combustion chamber 3. It is apparent that the same results will occur on the down stroke in relation to the other side of the engine.

It is apparent that when the working piston on one side of the engine is descending, subject to a pressure on its upper face, the compression piston on that side is acting as a suction piston drawing the mixture into the compressing cylinder. The great difference in pressure between the two sides of the working piston within a particular cylinder, would ordinarily result in leakage. This I prevent by means of the packing rings 18 and 19. As these rings must be compression rings in order to be effective, it is necessary, to permit them to be put in place, to utilize a bull ring 20 and a lower plate 21. This bull ring carrying the packing rings 18 and 19, is introduced into place, and the lower plate 21, which is annular in shape, is then introduced and serves to hold the lower ring 19, and also the bull ring in place within the cylinder. This lower plate 45 is held in position by means of screws 22. The lower plate extends downward a sufficient distance to embrace the rings 23 on the working piston 5 or 5^a, and hold them in place when the latter piston is at the lowest part of its stroke. The compression piston 6 or 6^a is in the form of an annular skirt 24, which extends upward around this lower plate when the piston is at the uppermost

position, so that the compression space is made as small as possible, and the necessary compression secured. By this device, the joint which separates the combustion chamber from the compression chamber is effectively packed by means of the compression cylinder rings in addition to the ordinary form of expansion piston rings.

The improved packing device can be employed in situations where the cross-over feature is not employed, as for instance, in engines where each cylinder is an entirety and the air or charge is compressed and fired in the combustion and compressing chambers located in the same cylinder.

The particular form of engine disclosed herein is not claimed in this application, but in my co-pending application, before referred to.

In accordance with the provisions of the patent statutes, I have described the principle of my invention, together with the apparatus which I now consider to represent the best embodiment thereof; but I desire to have it understood that the apparatus shown is merely illustrative and that the invention can be carried out in other ways.

Having now described my invention, what I claim as new and desire to secure by Letters Patent, is:—

1. An internal combustion engine, having a cylinder; a bull ring therein; there being a port passing through the bull ring; there being a second port in the cylinder to one side of the bull ring; and a packing ring between the two ports, said packing ring being held in place by means of the bull ring.

2. An internal combustion engine, having a cylinder; a bull ring therein; there being a port passing through the bull ring; there being a second port in the cylinder to one side of the bull ring; and a packing ring between the two ports, said packing ring being held in place by means of the bull ring; a second packing ring engaged by the bull ring, and a plate engaging with the second ring, and holding it in place.

This specification signed and witnessed this 30th day of Dec., 1911.

JOHN WILLOUGHBY.
